[57] CLAIM

The ornamental design for a sill vent for building foundations, as shown and described.

DESCRIPTION

FIG. 1 is a front perspective view of a sill vent for building foundations embodying my new design;
FIG. 2 is a top plan view thereof, the bottom plan view being identical thereto and not shown in the drawings;
FIG. 3 is a front elevational view thereof;
FIG. 4 is a rear elevational view thereof; and,
FIG. 5 is an end elevational view thereof, the end opposite being a mirror image of the end shown.
The cross-hatching in FIGS. 1, 3 and 4 represents screening and is understood to extend throughout the areas represented.

Fig.1.**Fig. 2.****Fig. 3.****Fig.4.****Fig.5.**
